ILLUMINABLE TOY VANITY KIT

Robert L. Lindsay, Hamilton, Ohio, assignor to Kenner
Products Company, Cincinnati, Ohio

Filed May 6, 1970, Ser. No. 22,829

Term of patent 14 years

Int. Cl. D3—99

U.S. Cl. D86—10

Fig. 1

Fig. 2

Fig. 3

FIG. 4

FIG. 5

FIG. 1 is a front perspective view of an illuminable toy vanity kit showing my new design;

FIG. 2 is a rear perspective view thereof;

FIG. 3 is a side elevational view;

FIG. 4 is a top plan view;

FIG. 5 is a bottom plan view; and

FIG. 6 is a perspective view thereof with the two sections of the vanity kit shown separated.

I claim:

The ornamental design for an illuminable toy vanity kit, substantially as shown.
